INVENTOR,
Frank Grant,
BY ATTORNEY.

UNITED STATES PATENT OFFICE.

FRANK GRANT, OF WESTFIELD, MASSACHUSETTS.

SHAVING-STICK HOLDER.

1,242,175.

Specification of Letters Patent.

Patented Oct. 9, 1917.

Application filed November 29, 1916. Serial No. 134,204.

To all whom it may concern:

Be it known that I, FRANK GRANT, a citizen of the United States of America, and resident of Westfield, in the county of 5 Hampden and State of Massachusetts, have invented certain new and useful Improvements in Shaving-Stick Holders, of which the following is a full, clear, and exact description.

10 This invention relates to a tubular container or casing more especially for a stick of shaving soap, which is slidably fitted therein, and in conjunction with which means are provided for the projection of a 15 suitable forward portion of the length of the stick for use,—while the casing forms a handle when using the stick,—and which means is operable for the withdrawal of the stick, after the same has been used, to entirely within the casing.

15 The invention further relates to means to coöperate between the forward open end of the casing and the shaving stick for preventing the entrance of water, lather, or 20 moisture into the casing between the wall of the latter and the sides of the stick.

25 And the invention further relates to certain features of construction of the parts and the combination of the parts as hereinafter more fully described.

30 The invention is described in conjunction with the accompanying drawings and is set forth in the claims.

In the drawings:—

35 Figure 1 is a central longitudinal section through the improved shaving stick holder.

Fig. 2 is a cross section on line 2—2, Fig. 1.

Fig. 3 shows the blank for the casing.

40 Fig. 4 is a horizontal cross section of the device showing a modification thereof.

Fig. 5 is a sectional view showing a modified construction of the device.

Fig. 6 is a sectional and plan view as 45 seen below line 6—6, Fig. 5.

Fig. 7 shows the end member as detached from the casing which is shown in vertical section.

50 In the drawings, A represents a tubular forwardly open case having an internal longitudinal rib *a* at one side thereof. B represents a stick of shaving soap of cylindrical form slidably fitting in the casing and having a longitudinal groove *b* along its side 55 and extending from end to end, in which

the said rib *a* engages, whereby the shaving stick is held against rotative movement relatively to the casing.

C represents a cap for closing the rear end of the casing, the same being fitted to rotate on such rear portion; and this cap has a screw D connected and engaged to be rotatable therewith and extended centrally within the casing for almost the entire length thereof, such screw engaging centrally in the 60 stick of shaving soap and serving, when turned in the one or other direction to cause the projection of a sufficient portion of the forward end of the stick beyond the open end of the casing to permit same to be used 65 while shaving and to be thereafter withdrawn entirely into the casing after use.

I prefer to produce the screw D from wire, and similar to a worm or cork screw, preferably with a forwardly extended 70 point *d*.

75 As shown, the wire screw or worm including the spiral coils has a short axial shank *f* which is provided with a laterally extended portion *g*, a longitudinally extended portion *h* engaged through a perforation *i* in the cap at one side of the center thereof, and a horizontally extended portion *j* which lies on and across the middle of the cap and has its extremity *k* inwardly 80 turned and engaged in or through another perforation *m* in the top of the cap at the other side of the center from the location of the first named perforation.

85 This simple and inexpensive form of screw 90 is also, in a simple and inexpensive manner, connected with the cap so that the screw must necessarily turn as one with the cap.

95 The stick of shaving soap may, in the production of the device which includes the stick and the holder therefor, be easily penetrated by the screw which will worm itself centrally thereinto, as may easily be performed by the assembler.

100 The stick is normally entirely inclosed within the casing, but may be projected outwardly as far or little as may be desired by the user by turning the screw through the rotation of the cap, and which action is effective, because of the nonrotatability of 105 the stick, to cause the outward advancement of the latter.

110 I provide a band G of elastic material surrounding the forward open end portion of the tubular casing, which band has a con-

strictive portion σ which protrudes beyond the casing end.

When the soap is entirely withdrawn within the casing the protruding portion of the band, by its constriction more or less inwardly overlaps the end of the casing and stick; and when the stick is forwardly projected to crowd itself through and beyond the forward protruding portion of the band, such latter named portion closely hugs the sides of the stick and prevents the entrance of the lather, water, moisture or any foreign substance between the sides of the stick and the wall of the casing, whereby foulness and any undesirable condition is measurably prevented.

A practical, cheap and effective construction of the casing having the internal longitudinal rib for the purpose described is one such as represented in Fig. 3, in which the casing is composed of a blank of sheet metal having near one margin thereof a plurality of longitudinally aligned narrow slots p and having at its other marginal portion a plurality of tongues q , the blank being bent around to tubular form, having the slot provided marginal portion a^2 inwardly bent to form the rib or flange and having the tongues of the other marginal portion engaged through said slots and disposed at the inside of the casing facewise on the inwardly bent portion a^2 .

This construction provides an efficient seam and also the required rib.

In the modification of the device shown in Fig. 4, the blank having the inwardly turned flange forming portion a^3 may be bent nearly, but not quite around to cylindrical form, and a wrapping s of hard, waterproof paper, or cloth, or similar thin flexible material, may be provided around and secured to the casing for retaining it in its cylindrical shape.

In the modification shown in Figs. 5, 6 and 7, the casing A instead of having a separately made cap at its rear end rotative relatively thereto, is made with an integral end wall t in and through which the shank portion of the screw D is engaged.

The screw externally of the rear end wall t , has a knob or disk u by which the screw is turned,—the screw being so engaged through the wall t as to be, while rotatable, endwise immovable.

The shank portion of the screw forward of the knob or disk u has an annular groove v

in which portions of the end wall t or the shell engage.

For practicability of construction the end wall is made with a comparatively small circular aperture w , as shown in Fig. 6, and of thin metal and has radial slits y extending from the perforation w to form lips or ears z which may be turned up, as shown in the lower portion of Fig. 7.

Now the screw may be entered through the space between the upturned lips to engage into the soap stick and to have the annular groove v assume a position in the plane of the end wall t , whereupon the portion u above the groove v by downward pressure will cause the lips to be forced down in or nearly to the same plane for their engagements in the groove v .

I claim:

1. In a device of the character described, a tubular casing having a rib extending longitudinally on the inner wall, adapted to guide a grooved stick of soap and prevent rotation thereof, an end member rotatable on the casing, and a wire in the form of an open helix secured to the end member and projecting axially of the casing to enter the soap and advance it in the casing on rotation of the end member.

2. In a device of the character described, a tubular forwardly open case composed of a blank of sheet metal having near one margin thereof a plurality of longitudinally aligned narrow slots and having on its other marginal portion a plurality of tongues, such blank being bent around to tubular form and having the slot provided marginal portion inwardly bent to form a rib and having the tongues of the other marginal portion engaged through said slots and disposed facewise on the first mentioned inwardly bent marginal portion, whereby such interengaged and inwardly bent portions form a longitudinal internal rib, a stick of shaving soap having a longitudinal groove slidably engaged in the casing and engaged by the rib, a cap rotatably fitting on the rear end portion of the casing and having a screw extending axially into the casing and engaging in the soap stick to advance the soap.

Signed by me at Springfield, Mass., in presence of two subscribing witnesses.

FRANK GRANT.
